COMBINED CIRCLE CUTTING TOOL AND PROTECTIVE COVER

John M. Snyder, New York, N.Y., assignor to Commercial Carpet Corporation, New York, N.Y., a corporation of New York

Filed Oct. 20, 1966, Ser. No. 4,356

Term of patent 14 years

(Cl. D54—13)

FIG. 1

FIG. 2

FIG. 3

FIG. 4

FIG. 5

FIG. 6

FIG. 1 is a top plan view of a combined circle cutting tool and protective cover;

FIG. 2 is a bottom plan view of a combined circle cutting tool and protective cover;

FIG. 3 is an elevational view of the combined circle cutting tool and protective cover with the cover in position;

FIG. 4 is an elevational view similar to FIG. 3 showing the new design in exploded relationship with the cover removed;

FIG. 5 is a perspective view of the tool portion of the combined circle cutting tool and protective cover; and

FIG. 6 is a perspective view showing the tool and cover together.

I claim:

The ornamental design for a combined circle cutting tool and protective cover, substantially as shown and described.
